United States Patent Office

Des. 180,793
Patented Aug. 13, 1957

180,793

VIBRATOR FOR A STORAGE HOPPER OR THE LIKE

Donald B. Lash, Willoughby Hills, Ohio, assignor of one-fourth to John M. Froelich and one-fourth to Carl Nehring, both of Cleveland, and one-fourth to George Arend, Willoughby Hills, Ohio

Application February 13, 1956, Serial No. 40,155

Term of patent 14 years

(Cl. D55—1)

Fig. 1

Fig. 2

Fig. 3

Fig. 1 is a perspective front view of a vibrator for a storage hopper or the like showing my new design;

Fig. 2 is an end elevational view of the vibrator illustrated in Fig. 1; and

Fig. 3 is a front elevational view of the vibrator illustrated in Fig. 1.

The rear portions not shown are substantially plain.

I claim:

The ornamental design for a vibrator for a storage hopper or the like, as shown and described.
